UNITED STATES PATENT OFFICE

2,552,716

LAWN SPRINKLER

Louis E. Holland, Jackson County, Mo.

Application August 11, 1947, Serial No. 767,887

3 Claims. (Cl. 299—68)

1

This invention relates to lawn sprinklers and particularly to those of the rotary spray type wherein the spray nozzle is carried by a rotary head actuated by a water jet from the nozzle.

In sprinklers of this character a packing is necessary to prevent leakage between the rotary sprinkler head and its support, which packing resists free rotation of the sprinkler head. Consequently, substantial water pressure is expended in turning the sprinkler head. Another difficulty with such devices is that the water pressure exerts an axial thrust between the head and its support which further increases resistance to turning and causes wear of the parts.

It is, therefore, a principal object of the present invention to provide sprinkler structure having a packing between the rotary head and its support which permits substantially free turning of the sprinkler head and which forms a leak-tight, substantially trouble-proof seal.

A further object of the invention is to provide a sprinkler wherein the rotary head is entirely free of axial thrust produced by the water pressure.

Other objects of the invention are to provide a sprinkler which is of simple construction and adapted to be economically manufactured; to provide a simple anti-friction bearing between the sprinkler head and its supporting spindle to carry the weight of the movable parts; and to provide a connection between the rotary seal and sprinkler head so that these parts rotate as a unit on the spindle.

In accomplishing these and other objects of the invention hereinafter pointed out, I have provided improved structure, the preferred form of which is illustrated in the accompanying drawing wherein:

Fig. 1 is a perspective view of a sprinkler embodying the features of the present invention.

Fig. 2 is a similar view of the sprinkler from the side opposite to that illustrated in Fig. 1.

Fig. 3 is a vertical section through the sprinkler.

Fig. 4 is a plan view of the sprinkler with the cover of the rotary head broken away to better illustrate the gearing which effects rotation of the sprinkler head about the axis of the spindle.

Referring more in detail to the drawings:

1 designates a sprinkler constructed in accordance with the present invention and which includes a base or stand 2, a spindle 3, a sprinkler head 4 and a swivel connection 5. The base 2 preferably includes a plate portion 6 having outwardly directed ears 7 for attaching leg members 8 and 9. The leg members are preferably formed

2

of strap material bent to provide substantially parallel ground engaging portions 10 and upwardly and inwardly extending portions 11 and 12 having terminals 13 that are attached to the ears 7 in any suitable manner, for example, by rivets 14.

Extending upwardly from the plate portion 6 is a boss 15 and a laterally directed extension 16 having an axial bore 17 connected with a vertical bore 18 in the boss 15 to form a water passageway 19 therethrough. The inlet of the bore 17 is internally threaded as at 20 to mount the threaded nipple 21 of a coupling 22, preferably for connecting a hose. The bore 18 extends through the top face of the boss 15 and is internally threaded as at 23 for mounting the spindle 3.

The spindle 3 comprises a tube 24 having a threaded end 25 that is tightened into the threads 20 23 to connect the axial passageway 26 therein with the water passageway 19 and form a rigid leak-tight connection with the base. The spindle is of sufficient height to mount the swivel 5 and head 4. The upper end is closed by a plug 27 for diverting water through a lateral outlet opening 28 in the spindle as best shown in Fig. 3, the opening being spaced above the boss 15 of the base so that it registers with the flow passageway in the swivel 5 as later described.

The swivel 5 includes a substantially T-shaped fitting 29 having a substantially cylindrical body 30 of larger internal diameter than the outer diameter of the spindle to accommodate packing elements 31 and 32 at the respective ends thereof and to provide an annular passageway 33 in registry with the lateral opening 28 of the spindle, the passageway 33 being separated from the packing elements by internal annular flanges 34 and 35 which have axial openings 36 through which the spindle extends. The flanges thus provide seats for packing washers 37 and 38 which encircle the spindle and are retained in sealing relation therewith by followers 39 and 40 that are sleeved on the spindle and which have external threads engaging internal threads at the ends of the cylindrical body 30 of the swivel. The followers are retained in adjusted position relative to the packing by jam nuts 41 and 42 that are turned on the threads of the followers and which engage the respective ends of the fitting as shown in Fig. 3. The followers may thus cooperate with the flanges to provide bearing surfaces to maintain coaxial position of the swivel on the spindle when the swivel rotates thereon as later described. Extending from the sleeve-like body

portion of the swivel in registry with the annular passageway 33 is a lateral branch 43 having an axial bore 44 in connection with the annular passageway 33 as shown in Fig. 3. The branch of the swivel is of sufficient length to accommodate threads 45 and to provide a smooth bearing portion 46 adjacent the cylindrical body 30 to mount a tie member 47 later described.

The sprinkler head includes a box-like gear casing 48 having a bottom 49 and side walls 50—51 and 52—53. The bottom of the casing has a depending boss 54 provided with an axial opening 55 to pass the casing over the end of the spindle.

Contained within the casing is a worm gear 56 having a hub 57 mounted on the spindle and fixed thereto by a suitable fastening means, such as a set screw 58 to secure the worm gear from rotation so that it provides a fixed orbit about which planetary gearing is caused to operate for effecting rotation of the sprinkler head on the spindle. The worm gear is engaged by a worm 59 fixed to a shaft 60 having the ends thereof journaled respectively in a bearing boss 61 which projects inwardly from the wall 50 and in a bearing contained in a plug 62 that is threadedly mounted in an opening 63 located in the wall 51 in alignment with the boss 61. Also mounted on the shaft 60 is a worm gear 64 which meshes with a worm gear 65 on a shaft 66 that extends across the shaft 60 and has one end mounted in a bearing boss 67 projecting from the wall 53 and in a bearing 68 that is carried by a plug 69 threaded in an opening 70 of the wall 52.

The shaft 66 projects through the bearing 67 and carries an impeller disk 71 having a circumferential series of laterally extending vanes 72 against which a jet of water is discharged from a secondary port 73 of a nozzle 74 later described. The disk includes a hub 75 that is mounted on a reduced extension 76 of the shaft 66 and is retained thereon by a nut 77.

The open top of the housing is covered by a plate 78 that is secured to the walls of the housing by fastening devices such as cap screws 79. The cover plate 78 includes a lateral extension 80 that projects beyond the side wall 50 and terminates in an ear 81 in which the nozzle 74 is mounted so that the port 73 thereof discharges a jet against the vanes 72 to effect rotation of the impeller disk 71. The nozzle is connected with the branch 43 by a tube 82 which is connected therewith by a union nut 83.

In order to support the gear casing on the spindle, the closure plug 21 in the upper end of the tubular spindle 3 includes a bearing cap 84 having an axial recess 85 for seating a ball bearing 86 which also engages in a recess 87 that is provided in the cover plate 78 of the gear housing as shown in Fig. 3. It is thus obvious that the weight of the gear housing and the parts supported thereby is carried on the ball bearing 86 so that the sprinkler head is adapted for free rotation about the axis of the spindle.

The tie member 47 is of plate-like shape and has one end attached to the gear casing by screws 88 and the other end has an opening 89 engaging over the cylindrical portion 46 of the branch 43 of the swivel member. With this connection, the casing causes the swivel member to rotate without placing strains on the connecting tube 82 or its couplings.

In assembling the sprinkler, the tubular spindle 3 is threaded into the boss 15 on the base or stand 2 and the swivel member 5 together with

the packing washers 37—38 and followers 39—40 carrying the jam nuts 41 and 42 are sleeved over the upper end of the spindle to register the passageway 33 with the lateral opening 28 of the spindle. The followers 39 and 40 may then be adjusted to properly press the packing against the spindle and the jam nuts 41 and 42 are tightened to maintain the adjustment. The gear casing 48 is then sleeved over the spindle followed by the worm gear 56 which is secured to the spindle by tightening of the set screw 58. The closure 27 is then applied to the open end of the spindle and sealed in position as, for example, by soldering or the like as indicated at 90.

The worm 59 and worm gear 65 are then positioned in the casing and the shaft 60 is moved through the opening 63 and gears so that one end thereof is rotatably supported in the bearing boss 61. The bearing plug 62 is then applied to the end of the shaft and threaded into the opening 63. The gears are fixed to the shaft in any suitable manner, after which the shaft 66 is similarly inserted with the worm 65 thereon meshing with the worm gear on the other shaft (Fig. 3). The impeller 71 is applied to the reduced extension 76 of the shaft 66 and secured thereto by the nut 77. The ball bearing 86 is then inserted in the conical recess 85 and the cover plate 78 applied so that the recess 87 therein engages over the ball and the marginal edge of the plate seats on the edges of the gear casing walls. The screws 79 are then applied. The swivel is then tied to the gear casing by passing the apertured end of the tie strap 47 over the lateral branch of the T fitting and the other end is attached to the gear casing by the screws 88. The nozzle 74 is assembled in the ear 81 of the cover plate and the tube 82 is connected therewith. The other end of the tube is connected with a lateral branch of the swivel by the union nut 83 which completes assembly of the sprinkler.

In using the sprinkler, the coupling 22 is connected with a source of water supply through a hose or the like (not shown) and when the water is turned on it flows through the passageway 19 into the passageway 26 of the tubular spindle from where it is discharged through the opening 28 into the annular passageway 33 for flow through the tube 82 to the nozzle 74.

The water is discharged in a stream or spray from the nozzle while a secondary jet is discharged through the secondary port 73 to impinge upon the vanes 72 of the impeller disk 71 to cause rotation thereof which effects planetation of the worm 59 about the worm gear 56 and causes the gear casing to be carried therewith in rotation about the axis of the spindle.

The nozzle and impeller wheel being carried by the casing will move therewith so that the stream of water is carried in a circular path about the axis of the spindle. Since the pressure of the water acts against the closure 27, there is no axial thrust on the gear casing that might tend to increase the resistance thereof to rotation. It is also obvious that the pressure within the swivel acts equally on the packing rings and there is no tendency to effect axial displacement of the swivel in either direction. Consequently, the sprinkler head and swivel member merely float on the ball bearing 86 to provide minimum resistance to rotation thereof under the power of the impeller disk. With this construction it is obvious that only a small jet need be used for effecting rotation of the impeller

wheel so that more water is dispersed by the spray.

From the foregoing it is obvious that I have provided a sprinkler that is of simple construction and which may be operated with a minimum loss of water pressure to effect rotation of the sprinkler head.

What I claim and desire to secure by Letters Patent is:

1. A sprinkler of the character described, including a stand, a tubular spindle carried substantially vertically on the stand and having an inlet at one end and a closure at the other, said spindle having a lateral outlet intermediate said ends, a head rotatable about the spindle, a nozzle carried by said head, a swivel consisting of a part separate from said head and having a passageway about the spindle in registry with said outlet, packing elements carried by said swivel on the respective sides of said passageway, packing glands carried by the swivel for compressing the packing elements in sealing relation with the spindle, a duct connecting the passageway of the swivel with the nozzle, an antifriction bearing between the closure and the head to support the head on said spindle, and a tie member connecting the swivel with said head and having a length to suspend the swivel spaced below said head for support of said swivel on the antifriction bearing and with said packing glands spaced below the head and above said stand respectively.

2. A sprinkler of the character described, including a stand, a tubular spindle carried substantially vertically on the stand and having an inlet at one end and a closure at the other, said spindle having a lateral outlet intermediate said ends, a head rotatable about the spindle, a nozzle carried by said head, a swivel consisting of a part separate from said head and having an annular passageway surrounding the spindle in registry with said outlet, packing elements carried by said swivel on the respective sides of said passageway, packing glands carried by the swivel for compressing the packing elements in sealing relation with the spindle, a duct connecting the passageway of the swivel with the nozzle, an antifriction bearing between the closure and the head to support the head on said spindle, a tie member connecting the swivel with said head and having a length to suspend the swivel in spaced relation below said head for support by the antifriction bearing and with said packing glands spaced from the head and above said stand respectively, an impeller carried by said head in the path of a spray discharged from the nozzle

when the sprinkler is in use, and means in said head connected with the impeller for rotating the head and swivel, said swivel being rotated through said duct and tie member connections.

3. A sprinkler of the character described, including a stand, a tubular spindle carried substantially vertically on the stand and having an inlet at one end and a closure at the other, said spindle having a lateral outlet intermediate said ends, a head rotatable about the spindle, a nozzle carried by said head, a swivel consisting of a part separate from said head and having an annular passageway surrounding the spindle in registry with said outlet, packing elements carried by said swivel on the respective sides of said passageway, packing glands carried by the swivel for compressing the packing elements in sealing relation with the spindle, a duct connecting the passageway of the swivel with the nozzle, an antifriction bearing between the closure and the head to support the head on said spindle, a tie member connecting the swivel with said head and having a length to suspend the swivel from said head for support on the antifriction bearing and with said packing glands spaced below the head and above said stand respectively, an impeller carried by said head in the path of a spray discharged from the nozzle when the sprinkler is in use, a gear member within said housing and having a hub engaging a bottom of said housing and fixed to the spindle for cooperating with the antifriction bearing in restricting longitudinal movement of the housing on said spindle, and a driving connection in the housing between said gear and the impeller for effecting rotation of the housing incidental to rotation of the impeller, said swivel being rotatable by the housing through said duct and tie member connections.
